METHOD AND APPARATUS FOR DIFFERENTIALLY WAVING HAIR

Joseph Torres, Brooklyn, N. Y.

Application December 29, 1937, Serial No. 182,194

12 Claims. (Cl. 132—36.2)

This invention relates to a device and method for waving human hair and more particularly relates to the permanent waving of hair which has previously been waved although the invention as will be understood is applicable to the complete waving of the hair.

The modern "permanent" waving processes successfully produce a reasonably satisfactory and permanent wave on the hair except for the new growth of straight hair which comes in adjacent the scalp after a comparatively short period of time. This new growth of straight hair soon nullifies the effect of the permanent wave and necessitates a re-waving operation in order to wave this newly grown portion of hair. With the previous processes, the waving of this newly grown portion of the hair presents serious difficulties inasmuch as the waving of this newly grown hair often has a bad effect on the previously waved portion, either destroying the wave in the previously waved portion or frequently imparting undesirable or uncontrollable waves or kinks to the previously waved portion, making it look uneven and unsightly. Aside from the unattractiveness of the wave untold discomfort is experienced on each combing of the hair.

In view of the large element of chance, hairdressers avail themselves of every opportunity to cut off the previously waved hair as they realize it is the only existent sure way to procure attractive waves. While the problem is most acute in previously waved hair it is nevertheless present even in unwaved hair as it is known that hair close to the scalp is always oilier and stronger than hair farther from the head.

Previously attempts have been made to encompass portions of hair to be waved in separate heating means but such processes require a plurality of heating units of varying lengths and heating capacity. The application of such a plurality of units consumes a large amount of the operator's time and causes the recipient of the wave discomfort. In addition to the above problems it has been found impossible to sufficiently control the heat within the heating means so as to impart to the hair either a uniform wave or variations found desirable by hairdressers and hair stylists.

It is an object of my invention to enable hairdressers to control the action of the curling solutions so as to either produce uniform waves or waves of any desirable gradation from the roots to the ends of the hair.

It is also an object of my invention to procure

more certain results than have heretofore been possible.

An object of my invention is to provide a method and device for waving hair in which the effect of the waving can be varied on various parts of the hair and one portion waved without affecting another previously waved portion if desired.

It is one of the objects of this invention to more effectively wave the straight hair which grows in adjacent to the scalp to give it a so-called "permanent" wave and differentially wave the hair in the previously waved portion of the hair which may still be in good condition so as not to wave it too much and cause kinking.

Another object of this invention is to provide a device which is particularly adapted for reducing the effect of the waving solution on the ends or previously waved portion of the hair, while still permitting a strong and satisfactory wave on the new straight portions of hair which have grown in.

Other advantages of my invention lie in the time saved the operators, relief from discomforts caused by a plurality of heating means, and the equal facility with which my method and devices can be applied to all types of hair curling operations.

My present invention provides a process and a device which makes possible differential waving of the hair by controlling the effect of the curling solution. This method has great advantages over previously used methods which attempted, with little success, to control the heating means. In this method newly grown hair may be waved without giving the same degree of wave to previously waved portions of the hair to thereby balance the waving effect. It is also possible, according to the process disclosed in this invention, to impart a new wave to the entire length of hair which may or may not have been previously waved, and also to impart a special or especially tight or loose curl to selected portions of the hair as, for example, toward the end of bobbed hair, all of which is impossible with previous hair waving systems, which cannot curl next to the roots without overcurling the ends.

Further objects and advantages of this invention will appear from the following description thereof taken in connection with the attached drawings which illustrate several forms of the embodiment of the invention and in which:

Figures 1, 2, 3 and 4 show the use of my device and a representation in perspective of the steps taken in the roll curling of hair.

Figure 5 and Figure 6, respectively, show plan views of the non-porous pliable shielding material and the neutralizing pad ready to be positioned thereon.

5 Figures 7, 8 and 9 show views similar to those of Figures 1, 2, 3 and 4 when curling previously curled hair.

10 Figures 10, 11, 12, 13 and 14 show my device and a representation in perspective of the steps taken in the spiral curling of hair.

15 In the roll curling of hair, as shown in Figures 1 to 9 of the drawings, the hair on the head is divided into a plurality of tresses or strands 17 which are clamped between the two parts of a clamp and insulator 18 which separates the strands 17 from other strands on the head and protects the scalp from the heat of the waving heaters. After the strands 17 have been separated and clamped in the clamp and insulator 18, they are first wetted with a waving or curling solution, of which many compositions are known. One suitable composition of waving solution is composed of potassium sulfite, ammonium carbonate and water.

20 25 This waving solution is applied to the tress or strand 17, and in the normal waving operation, the end of the strand 17 is clamped in a curling rod 20 and the strand is rolled or wound on the curling rod, as indicated, for example, in Figures 2 and 3, wrapped with a non-porous foil carrying a pad moistened with the curling solution, and the heating element 23 applied to the rolled and wrapped strand to heat and vaporize the curling solution to effect permanent waving of the hair. In this method of waving as previously practiced 30 the same degree of curling or waving cannot be applied to the entire strand, so that both the ends and the portion next to the scalp are waved to substantially the same degree because the end portions being on the inside of the roll on the curling rod 20 are curled tighter, and if the end portions have been previously waved, kinking, or 35 undesired curling, is imparted to the ends.

40 According to my invention, however, it is possible to shield the end portions and to neutralize the effect of the curling solution and the tighter wind on the end portions to permit a strong wave to be imparted to the new hair which has grown in next to the scalp without too strongly waving or kinking the end portions.

45 50 This differential waving is effected by first applying the curling solution and winding the straight end portion 19 or the previously waved portion 26 of a strand 17 on the curling rod 20, and when the end of the previously waved portion 26 or the straight end 19 is reached enclosing this first wound portion of the strand 17 in a shield or foil 21 which may be composed of tin foil or other non-porous material carrying a pad 25 which is impregnated with a material for neutralizing the curling solution applied to this portion of the hair. This neutralizing pad may be impregnated with sodium dichromate or ammonium chloride, or a mixture of the two, and the pads 25 may be of different size or different 55 strengths of impregnation so as to either completely or partially neutralize the waving effect in the end portion of the strand. Instead of being applied on a pad, the neutralizing material 60 may be made into a paste and applied directly to the shield or foil 21.

65 70 After the shield 21 and neutralizing material or pad 25 have been applied to the wound end portion of the hair on the curler 20, as indicated 75 in Figures 2 and 8, the remaining portion of the

strand 17 is then wound on the curler 20 with the shield 21 surrounding the end portion of the strand 17 and enclosing therein the neutralizing material or pad 25 which is impregnated with the neutralizing chemical. When the complete 5 strand is wound on the curling rod 20, the rod is clamped in the clamps 22 constituting part of the clamp and insulator 18, and a further sheet of tin foil or other non-porous material 24, which may carry a pad of cotton, or Canton flannel, moistened with the curling solution, is applied around the wound strand, as indicated in Figure 9, and the wound strand enclosed in a clamping and heating element 23, so that the entire roll of the strand 17 can be subjected to the steaming and 15 heating action which causes the curling solution to act upon the exposed portion of the strand 17, while at the same time the neutralizing material on the foil 21 or the pad 25 enclosed in the inner shield 21 acts upon the ends of the hair 20 enclosed in the inner shield, so that the ends of the hair inside the shield 21 are waved to a lesser degree than the hair outside the shield 21, whereby a good wave may be imparted to the strand of hair next to the head and a lesser degree of waving applied to the ends and especially the previously waved ends 26 of the strands of hair.

25 30 35 While the neutralizing material of different amounts or strengths can be used to effect any desired degree of neutralization of the curling action on the ends of the hair, the use of the foil or shield 21 to enclose the end portion where the curling action is to be reduced or neutralized is of vital importance, as without this shielding effect of the foil 21, the vapors of the curling solution would penetrate entirely through the roll of hair on the rod 20 and curl all portions, whereas by the use of the shielding foil 21 penetration to the end portion of the hair is prevented.

40 45 50 I have shown in Figure 10 and Figure 11 a tress of hair 27 as it grows from the head. Portions to be differentially treated are shown uncurled 28 and curled 29. The hair in Figure 12 is shown wound upon a curling rod 30 suitable for the spiral curling of the hair. The shield 21, carrying the pad 25 on which the neutralizing material is applied, is shown positioned to be wound for the selective treatment of the ends of the strands of hair in this type of hairdressing. In Figure 13, I show the hair completely wound on the curling rod and the pad 21 in position for the application of heat. The heating means 31 usually used in spiral waving is shown in Figure 14 with the hair wound on the curling rod positioned therein.

55 60 65 In this embodiment of the invention, the portion of the hair outside the shield 21 is subjected to the full waving action of the waving solution while the portion inside the shield is protected from the waving action and the waving action partly neutralized by the neutralizing material on the pad 25.

70 75 80 It will be understood that each tress of hair is waved separately after being wound on a curling rod and encased in a heating unit. When the heating means is energized the curling solution vaporizes, and it together with the heat imparts a "permanent" wave to the air. It happens, however, that in the portions containing the neutralizer and which are shielded by the non-porous material that the heat causes the neutralizer to be dispersed with the curling solution where it neutralizes the curling solution to any desired degree. The shield has the effect of limiting the action of the neutralizer to any desired por- 75

tions. I may effectively wave any selected portions to any desired degree even without affecting the unselected portions by varying the amount of neutralizer within the shielding means.

5 I have shown in the foregoing drawings two of the most popular methods for the permanent waving of the hair. It is easily seen that my method and device is equally applicable to each of the methods shown and to other methods, and 10 therefore not limited to any particular type of hairdressing.

One of the much used hair treating solutions is composed of potassium sulfite, ammonium carbonate and water. I have found that sodium dichromate or ammonium chloride, or a mixture 15 of the two, can be used to neutralize the effect of the above solution to any desired degree by varying the strengths of the ingredients. Furthermore, these materials are solid at ordinary temperatures, making them especially desirable for hair treating purposes as the absorbent material, such as flannel or gauze 25, can be impregnated in the liquid phase with a solution of the neutralizing material or materials and then allowed 20 to dry, or these materials may be made into a paste and applied directly to the foils 21. The solid material is much more easily handled for purposes of distribution and on application causes the customer no inconvenience. One readily realizes that I am not limited in the number 25 or size of the pads 25 that I may apply, nor in the amount of the neutralizer that may be absorbed in each pad. These features enable me to achieve wide variations and a degree of certainty here- 30 tofore unknown in the hairdressing art.

While in theory differential waving has been possible in the past by controlling the degree of heat, it is well known that control of heating means has led to very uncertain results. Furthermore, the plurality of units needed to differentially heat varying lengths of hair on different persons and also to differentially heat portions of each tress has caused the recipient of the wave discomfort, consumed the time of the operator 40 and multiplied the amount of equipment to be bought and manipulated, thereby materially increasing the cost of "permanent" waving. I, having experienced the difficulties inherent in such operations, have produced and described herein a device and a method which enables me to neutralize in whole or in part the effect of the curling solution, thereby enabling me to differentially wave the hair even while using the same heating means. In the drawings I have illustrated 45 differential waving within a single heating unit which has heretofore been unknown. The method and the device for the differential waving of the hair by controlling the effect of the hair treating solution and shielding one portion of the hair 50 from the effect of the treating solution on the other portion as shown in this application is unique in the hair treating art.

While I have shown two of the preferred methods of waving hair and the application of my method and device thereto, it is to be understood 55 that my invention is not limited by the description disclosed herein, but that modifications may be made within the scope and spirit of the present invention, and I therefore desire a broad 60 interpretation of the disclosure within the scope and spirit thereof and of the claims appended hereinafter.

It is to be further understood that "curling 65 solution neutralization or neutralizer" has been 70 used to represent any degree of neutralization 75

however small to complete neutralization, and that other neutralizing and curling solutions than those specifically mentioned may be used.

I claim:

1. The method of differentially waving selected 5 portions of hair which comprises, wetting the hair with a curling solution, winding portions thereof to be protected on a curling rod, placing on said wound hair a neutralizing material capable of neutralizing the effect of the curling solution on the application of heat, surrounding the neutralizing material and previously wound hair with a non-porous shield, thereby shielding the selected portions so that the curling action and neutralizing action will not pass from one portion to the other, winding the remaining hair on the curling rod and heating to vaporize the curling solution: 10 15

2. The method of differentially waving selected 20 portions of hair which comprises, wetting the hair with a curling solution, winding portions thereof to be protected on a curling rod, placing on said wound hair a neutralizing material capable of neutralizing the effect of the curling solution on the application of heat, shielding the 25 first wound portion from other portions of the hair, winding the remaining hair on the curling rod and heating to vaporize the curling solution.

3. A method of selectively waving hair, which 30 comprises wetting the hair with a curling solution, coiling a part of a tress of such hair on a curling rod, applying to the hair on the curling rod a pad containing curling material neutralizer, superimposing on the pad a non-porous shield, 35 winding the remaining portion of the tress upon the curling rod, covering the remaining hair with a second shield, applying heat thereby producing the desired wave and neutralization. 35

4. The method of differentially waving selected 40 portions of hair, which comprises wetting the hair with a curling solution, neutralizing the effect of the curling solution in selected portions thereof, shielding the portion to be neutralized from the effect of the curling solution on the unneutralized portion and heating to vaporize 45 the curling solution and to impart wave to the hair.

5. The method of waving hair which comprises 50 wetting the hair with curling solution, selecting portions to be differentially treated, winding a portion of the hair on a curling rod, applying to said wound portions curling solution neutralizers of varying strength, shielding said first wound portion to prevent interpenetration 55 of neutralizers and curling solution into unselected portions, winding the remaining portion on the curling rod and heating to produce the desired wave and neutralization.

6. The method of rewaving hair, which comprises the steps of separating the hair into 60 tresses, applying hair curling solutions to the hair, coiling the previously waved hair on a curling rod, neutralizing the waving solution in the previously waved portion, shielding the chemicals in the previously waved hair from those in 65 the newly grown hair, winding the newly grown portion of the hair tightly on the curling rod, and subjecting the coiled hair to the action of heat.

7. As an article of manufacture, a hair treat- 70 ing pad adapted for the differential waving of hair, which comprises a porous pad, adapted to be shaped to surround hair on a curling rod and impregnated with curling solution neutralizer.

8. As an article of manufacture for hair wav- 75

ing, a shielding material carrying a hair waving neutralizer thereon.

9. As an article of manufacture for differential waving of hair, a shielding material of foil or the like having a hair curling neutralizer thereon.

10. As an article of manufacture, a hair treating pad adapted for the differential waving of hair, which comprises an absorbent pad, adapted to be shaped to hair on a curling rod and impregnated with curling solution neutralizer, and a non-porous shield encasing said pad.

11. As an article of manufacture, a hair treating pad which comprises an absorbent flexible material impregnated with a solid curling solution neutralizer.

12. As an article of manufacture, a hair treating pad adapted for the differential waving of hair, comprising a liquid and gas impervious wrapping sheet, and an absorbent flexible pad impregnated with a solid curling solution neutralizer secured to said sheet.

JOSEPH TORRES.
